UNITED STATES PATENT OFFICE.

ALDEN A. STEWARD, OF RUTLAND, VERMONT.

FIRE-CHECK.

958,944.

Specification of Letters Patent. Patented May 24, 1910.

Application filed September 13, 1909. Serial No. 517,545.

To all whom it may concern:

Be it known that I, ALDEN A. STEWARD, a citizen of the United States, residing at Rutland, county of Rutland, State of Vermont, have invented certain new and useful Improvements in Fire-Checks, of which the following is a specification, reference being had therein to the accompanying drawing.

This invention relates to a fire check and particularly to a structure adapted to be disposed between the source of supply of an explosive mixture and the engine or motor in which said mixture is to be used.

The invention has for an object to provide a fire check comprising a laminated structure of metallic plates and gauze disposed in contact with each other and with the edges thereof parallel with the flow of the fluid through the check.

Other and further objects and advantages of the invention will be hereinafter set forth and the novel features thereof defined by the appended claims.

In the drawing—Figure 1 is a central vertical section showing the invention applied; Fig. 2 is a front elevation of a diaphragm having a check mounted therein; Fig. 3 is a vertical section therethrough; Fig. 4 is a detail perspective of the check with parts broken away; Fig. 5 is a vertical section showing a modified application of the check; Fig. 6 is a vertical cross section showing a modified form of the check; Fig. 7 is a detail perspective of a modified form of the metallic plate used in the check; and Fig. 8 is a sectional view of a modified form of check.

Like numerals of reference refer to like parts in the several figures of the drawing.

The numeral 10 designates the fire check which is composed of a series of metallic plates 11 alternated with sheets of metallic gauze or reticulated material 12 clamped in close contact with each other by any desired means for instance a binding wire 13 as shown. This laminated structure is mounted in any desired manner for instance upon a diaphragm 14 as shown in Figs. 1, 2 and 3. This diaphragm may be mounted in any desired manner to present the edges of the plate and gauze parallel with the flow of the fluid therethrough. It is shown in Fig. 1 as mounted in a casing 15 having a communicating pipe 16 from a supply and a similar pipe 17 extending to an explosive engine. In Fig. 5 this diaphragm is shown

as disposed diagonally of a pipe or conductor 18. The laminated layers forming the check are here shown as secured in contact with each other by a binding wire but any other desired means may be used and the plate 11 may be perforated as shown at 19 in Fig. 7 in order to secure a lateral circulation or otherwise constructed as preferred.

Fig. 6 illustrates a modified form of the invention wherein a metallic sheet 20 and gauze 21 are spirally coiled upon each other to form a circular body which may be conveniently introduced into a pipe or other fluid conductor with its axis parallel to the flow of fluid therethrough.

Fig. 8 illustrates a modified form of the invention wherein annular corrugated plates of metal 25 are used in connection with intermediate sheets of gauze 26 the whole being inclosed within a perforated casing 27 disposed in a pipe or other receptacle 28. This casing is threaded at 29 so as to retain it in position and the head thereof is provided with a socket or tool hold 30. The central space in the laminated plates communicates with a feed opening 31 in the receptacle 28 so that the fluid passes from the receptacle into contact with the edges of the plates and gauze and thence outward through the opening in the receptacle as indicated by arrows in Fig. 8.

In the operation of the invention the explosive fluid mixture is drawn in one direction through the check by the suction action of the engine or motor while the structure of the check prevents the gas or flame passing therethrough in a reverse direction under high pressure back firing of the engine. As the gaseous mixture flows edgewise through the collected strips and gauze it is exposed to the largest area of metallic surface and chilled below the point of combustion while the alternate layers produce eddies in the gas which break up the oscillations thereof and thereby check the propagation of flame. Gas under pressure will ordinarily pass through fire checks composed of superposed layers of gauze as the eddies produced are uniform owing to the configuration of the structure and passages. It has been found by experiment that imperfect contraction is produced by the use of a plate and interposed wire gauze and the flow of fluid is increased while the resistance thereto breaks up the oscillations of the flame and

checks combustion. Ordinary wire gauze or screen presents in its structure a large number of orifices in a thin plate while the metallic sheet held in contact therewith produces non-uniform contracted orifices which pass more fluid in a disturbed condition and check the production of flame. The sheet metal strips also act to strengthen the structure and prevent warping thereof under high pressure back fires while if the strips be perforated a lateral flow of fluid may be secured through the check.

The invention therefore presents a simple, efficient and economically constructed form of fire check adapted to prevent the communication of flame to the source of supply from a motor under any operating pressure.

Having described my invention and set forth its merits what I claim and desire to secure by Letters Patent is—

1. A fire check comprising laminated alternate plates and reticulated strips disposed with the edges thereof parallel with the flow of fluid therethrough.
2. A fire check comprising alternate layers of metallic plates and gauze disposed with the edges thereof parallel with the flow of material therethrough.

3. A fire check comprising alternate layers of metallic plates and gauze disposed with the edges thereof parallel with the flow of material therethrough, and means for binding said plates and gauze into contact with each other.

4. A fire check comprising alternate layers of metallic plates and gauze disposed with the edges thereof parallel with the flow of material therethrough, and a binding wire surrounding said plates and gauze for holding them in contact with each other.

5. A fire check comprising alternate layers of apertured metallic plates and gauze disposed with the edges thereof parallel with the flow of the fluid therethrough.

6. A fire check comprising a diaphragm having mounted therein alternating layers of metallic plates and gauze disposed in contact with each other and with their edges parallel with the flow of fluid therethrough.

In testimony whereof I affix my signature in presence of two witnesses.

ALDEN A. STEWARD.
